UNITED STATES PATENT OFFICE.

FRANKLIN A. SMITH, JR., OF PROVIDENCE, RHODE ISLAND.

BUTTON-FASTENER.

SPECIFICATION forming part of Letters Patent No. 276,638, dated May 1, 1883.

Application filed February 28, 1883. (No model.)

To all whom it may concern:

Be it known that I, FRANKLIN A. SMITH, Jr., a citizen of the United States, residing at Providence, in the county of Providence and State of Rhode Island, have invented certain new and useful Improvements in Devices for Attaching Buttons to Fabrics; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to an improved device for attaching buttons to garments or other fabric, whereby the use of setting-instruments is avoided.

20 My invention consists essentially of a fastener or holder made from wire or cut from sheet metal and having two depending legs united at the upper end, and thereby forming a loop, said loop portion being bent or formed at right angles with the legs, the latter adapted 25 to pass through the fabric from the upper surface thereof.

25 In the accompanying drawings, (greatly enlarged,) Figure 1 represents a perspective view of my button attachment. Fig. 2 represents 30 the same as it appears in the garment before bending the leg. Fig. 3 represents my device complete as inserted in the fabric and ready for use.

35 In the drawings, A is the fastener or button-attaching device, preferably formed of flat wire and consisting of the rounded loop a and sides a' , the latter being bent at right angles to said loop and near the upper end thereof, thereby forming the two parallel legs a^2 , as shown in 40 Fig. 1.

40 In Fig. 2 I have represented my device A as being in position to enter the upper side of the fabric, (see dotted lines,) while the full lines represent the same when in position after passing the legs a^2 through the fabric, one of the

legs being bent back, as shown also by dotted lines.

The operation and use of my improved button attachment is as follows: The button being selected, which may be an ordinary metallic suspender or flat button, the legs a^2 of the device are first passed through said button, after which the legs are inserted or pressed through the fabric until the fastener assumes the position shown in Fig. 2, and finally one 50 of the legs is bent back, as shown in Fig. 3, thereby presenting a broad retaining surface 55 against the back side of the fabric.

I may make the ends of the legs a^2 pointed or beveled for more readily entering the fabric, instead of first making two openings therein for the insertion of said legs, an advantage derived 60 from this method over the use of a long slot in the fabric being less damage to said fabric, as the two openings prevent the holder from turning and is more rigidly secured thereto, and at the same time allows the holder to be removed when desired. The holder is always inserted 65 from the upper surface of the fabric, having first been passed through the button, the whole being used and applied without the aid of a setting-instrument.

With proper care and economy my improved button-holder can be detached and reused several times.

Having thus described my invention, what I claim as new, and desire to secure by Letters Patent, is—

The improved button attachment A, consisting of the loop a , provided with two depending 80 sides, a' , the latter bent at right angles to said loop and forming penetrating legs a^2 , the whole arranged and adapted for use substantially as shown and described.

In testimony whereof I have affixed my signature in presence of two witnesses.

FRANKLIN A. SMITH, JR.
